CLAIM

The ornamental design for a teller machine wall unit or
the like, substantially as shown.

DESCRIPTION

FIG. 1 is a front and left side perspective view of a teller

machine wall unit or the like showing our new design;

FIG. 2 is a front elevational view thereof;
FIG. 3 is a left side elevational view thereof, the right
side being identical;

FIG. 4 is a sectional view taken along line 4—4 of FIG.
3;

FIG. 5 is a top plan view thereof; and

FIG. 6 is a bottom plan view thereof.
